US0D1058206S

(12) United States Design Patent (10) Patent No.: US D1,058,206 S
(45) Date of Patent: * Jan. 21, 2025

(54) ARMCHAIR

(71) Applicant: Mingquan Li, Ningbo (CN)

(72) Inventor: Wenzhu Zhong, Zhejiang (CN)

(73) Assignee: Mingquan Li, Ningbo (CN)

() Term: 15 Years

(21) Appl. No.: 29/959,336

(22) Filed: Aug. 25, 2024

(51) LOC (15) Cl. 06-01

(52) U.S. Cl.

USPC D6/371

(57) CLAIM

The ornamental design for an armchair, as shown and described.

DESCRIPTION

FIG. 1 is a front, left, top perspective view of an armchair, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 3;

FIG. 11 is an enlarged view of detail 11 in FIG. 3;

FIG. 12 is an enlarged view of detail 12 in FIG. 4;

FIG. 13 is an enlarged view of detail 13 in FIG. 5; and,

FIG. 14 is an enlarged view of detail 14 in FIG. 5.

The dash-dot-dash broken lines are for notating enlarged views and form no part of the claimed design.

1 Claim, 13 Drawing Sheets
